APPARATUS FOR WRAPPING CARTONS, BLOCKS, AND SIMILAR ARTICLES IN PAPER
OR LIKE MATERIAL.

Application filed January 21, 1926, Serial No. 82,812, and in Great Britain January 19, 1925.

This invention relates to apparatus for wrapping cartons (e. g. cigarette-containing cartons), blocks and other articles in paper, metal-foil or like sheet material. The apparatus provided by the invention is applicable in general to the wrapping of articles or groups of articles (e. g. bundles of cigarettes) which approximate to a rectangular form.

10 The invention deals with apparatus of the type in which the articles to be wrapped are advanced one at a time (by a continuously-moving conveyor) past folding devices which operate to fold a wrapper about each article in such manner as to form an open-ended pouch which encloses the forward end, the top and bottom, and the sides of the article, and which projects at its open end beyond the adjacent rear end of the article 15 by an amount sufficient to allow of the projecting portion being folded down to complete the wrapping.

In a typical machine of the above class the articles are advanced along a horizontal support by an endless conveyor provided with upstanding elements (hereinafter referred to as pushers) spaced apart and each adapted to engage the rear end of the article 20 and to push the latter along the support and between stationary guides which operate to fold a wrapper about the article in the manner described above. The wrapper, which is fed across the path of the conveyor in a plane at right-angles thereto, is engaged by 25 the front end of the article and carried forward thereby past the guides aforesaid which perform the folding operations. The partially wrapped article is then removed 30 from the conveyor and the operations involved in folding down the open end of the wrapper then performed.

When the conveyor is of the type provided with pushers adapted to make end-on engagement with the rear faces of the articles, it is essential that the partially wrapped articles be moved ahead of the conveyor at a speed greater than the linear speed at which the conveyor is driven; otherwise the pushers as they reach the end 45 of the conveyor path would be liable to foul the projecting portion of the wrapper at the rear end of each article.

The present invention is concerned with

means for removing the partially wrapped articles from the conveyor and with means 55 for tucking in the sides of the projecting portion of the wrapper.

According to the invention a wrapping machine of the type hereinbefore described and having transfer members operable to engage in turn each partially wrapped article as it approaches the end of the conveyor and to move said article forward in advance of the conveyor, is characterized in that the transfer members aforesaid are arranged to 60 engage the rear end face of the partially wrapped article and to push the latter forward 65 clear of the conveyor.

In wrapping apparatus of the type with which this invention is concerned it has 70 hitherto been proposed, for the purpose of advancing the partially wrapped articles clear of the conveyor, to employ as transfer members a pair of rollers (having tucking elements carried thereby) driven at a peripheral speed greater than the linear speed 75 of the conveyor and arranged to engage the sides of the partially wrapped article and by frictional engagement therewith to drag 80 the latter forward clear of the conveyor.

An advantage of the arrangement embodying this invention is that the action of the transfer members (which make a positive end-on engagement with each article) is 85 independent of small variations in the width of the articles on which the wrapping operations are performed.

In the preferred form of the present invention the movement of the transfer members to engage the aforesaid end face of the partially wrapped article is effected in a direction (e. g. aslant the path of the conveyor) such that the transfer members first engage the sides of the projecting portion of the wrapper and close said sides against the end face of the article, the transfer members thereby constituting tucking elements as well as means to advance the article ahead of the conveyor. Conveniently the transfer members are located on opposite sides respectively of the conveyor and are mounted for reciprocatory movement in a horizontal plane, the travel of each member being such that it first enters the path of the conveyor (preferably in a slanting direction) then moves along said path (during which time

it pushes a partially wrapped article in front of it) and finally recedes therefrom and returns to its initial position by a backward movement in a direction substantially parallel with the conveyor path.

According to a feature of the invention the means for reciprocating the transfer members are such that each member moves parallel to itself throughout its whole travel.

10 With this arrangement the transfer members operate smoothly and with certainty to fold in the sides of the projecting portion of the wrapper and to maintain the folds while the article is advanced clear of the 15 conveyor.

An example of an apparatus embodying the foregoing and other features of the invention will now be described with reference to the accompanying drawings in 20 which:—

Figure 1 is a side elevation showing certain parts of the said apparatus, Figure 2 is a plan of Figure 1, and Figure 3 is an end-elevation (looking toward the left in Figure 2) of the said apparatus, Figure 4 is a perspective view of the completely wrapped package, Figures 5 and 6 are perspective views of an article with its wrapper, as they appear at different stages of the wrapping 30 of the said article, Figure 7 is a sectional view, in perspective of the hereinbefore mentioned folding-blades, Figures 8 and 9, respectively, are a plan and end view (partly in section) of the said folder-blades, Figures 35 10 and 11 are detail sectional views showing a modified arrangement of folding-blades, and Figures 12 and 13 are sectional views of the aforementioned chute, and adjacently disposed members. Figures 4 to 13 inclusive 40 are drawn to a larger scale than are Figures 1, 2, and 3.

A pair of side-frames 1 and 2 are provided with bosses in which certain spindles and shafts, which will be referred to later, are 45 supported; on the upper portions of the said side-frames 1 and 2, various other constituent elements of the apparatus are supported.

A magazine is supported in a vertical position, and a number of the articles to be wrapped are deposited therein by an attendant.

The said magazine comprises two side-members 3 and 3^a, both of which are supported by bosses on a pair of spindles 4 and 5 which extend from a bracket or standard (not shewn) secured on the upper portion of the side-frame 1.

Continuously moving pushing means are provided and operable to push each of the said articles, in succession, through an opening in the lower end of the said magazine, and actuate the said article to travel along a rectilinear path, and thereby to come into engagement with a wrapper 6, (which is fed 60 by hand or by any suitable actuating means

between the elements 7 and 8 of a guiding device, to a receiving element 9, in such manner that the said wrapper 6 will be supported temporarily in a plane intersecting the path along which the said articles are actuated to travel).

Folding means are provided which co-operate with the forward travelling movement of the said article to fold the wrapper 6 into the form of an open-ended pouch or pocket-like covering on to the said article, and operable means are provided whereby portions of the wrapper 6, which project beyond the article, at the open end of the pouch or pocket-like covering, can be folded down on to the adjacently disposed end of the article.

According to my invention, the said pushing means comprise a pair of endless chains 10 and 10^a which are supported on sprocket wheels 11, 11^a, 12 and 12^a, arranged on conveniently arranged shafts. One of the said shafts, on which the sprocket-wheels 12 and 12^a are secured, is shewn at 13, and is supported in bosses 14^a and 14^b provided respectively on the side frames 1 and 2. Continuously rotative movement is imparted, by means of an electric-motor, or other source of power, to the shaft 13 and then to the sprocket-wheels 12 and 12^a in such manner that the upper runs of the chains 10 and 10^a will be actuated thereby to travel in a direction from left to right of Figures 1 and 2.

A number of transversely arranged cross-bars 14 are supported at equally spaced distances from each other along, and are actuatable by means of, the pair of chains 10 and 10^a. On each side of said cross-bars 14 a slot is provided, and a pusher 16 is adjustably secured, (by means of a screw, not shewn, inserted from the underside of the cross-bar 14 into the base-portion of the pusher 16) in any desired position between the respective ends of its corresponding cross-bar 14.

The cross-bars 14 and corresponding pushers 16 are actuatable by the chains 10 and 10^a in such manner that thereby each of the articles 17 (which are contained in the aforementioned magazine) can be pushed, in succession, by a corresponding pusher 16 through an opening 18 provided at the lower end of the said magazine and caused to come into engagement with a corresponding wrapper 6.

A pair of support-plates 19 and 19^a are secured on the corresponding side-frames 1 and 2 and are adapted to support the articles 17 in the said magazine and on their path of travel from the lower end of the said magazine to the position at which each of the said articles 17 is caused on its turn to engage with a wrapper 6.

The afore-mentioned folding-means, which are adapted to co-operate with the forward travelling movements of the articles 17 along the aforesaid path and thereby to fold the

corresponding wrappers on to the respective articles, comprise the lower end of the element 8 of the aforesaid guiding device, a pair of top plates 20 and 20^a, a pair of bottom-plates 21 and 21^a, a pair of first side-folders 22 and 22^a, a pair of bottom-side-folders 23 and 23^a, a pair of top side-folders 24 and 24^a, and a pair of fold-retaining members 25 and 25^a.

10 The bottom-plates 21 and 21^a are of such convenient lengths as to constitute supporting means for those articles 17 which are actuated to travel from the aforementioned wrapper-applying position to that part of the apparatus which is adjacent to the hereinbefore mentioned vertically arranged chute.

15 A pair of adhesive applying discs 26 and 26^a may be provided and adapted to impart 20 a supply of adhesive matter to portions of the wrapper 6 which are folded on to the respective sides of the article 17.

20 The said lower end of the element 8 of the guiding-device, the top-plates 20 and 20^a, 25 the bottom-plates 21 and 21^a, and the first side-folders 22 and 22^a, co-operate with the forward travelling movement of the article 17 and wrapper 6 to fold the said wrapper 6 on to the front end of, the upper-surface 30 of, the lower surface of and the sides of the article 17.

25 The bottom-side folders 23 and 23^a then co-operate with the continued further forward travel of the said article 17 and wrapper 6, to fold the lower projecting side-portions of the said wrapper 6 on to the article 17.

30 Later, the top side-folders 24 and 24^a contact with the said forward travel of the article 17 and wrapper 6 to fold the upper projecting side-portions of the wrapper 6 down, and on to those already mentioned 35 respective lower-side-portions of the said wrapper which have been folded, in the manner and by the means just described, up and on to the sides of the article 17, so that the article 17 with its wrapper 6 will be caused to appear as shewn in Figure 5.

35 The fold-retaining members 25 and 25^a are adapted to press the hereinbefore described folded side-portions of the wrapper 6 on to the respective sides of the partially wrapped article 17.

40 No specified claim is made, or intended to be made, for the employment (in apparatus of the character set forth) of the said article containing magazine, the support-plates 19 and 19^a, the said guiding-device, the top-plates 20 and 20^a, the bottom-plates 21 and 21^a, the first side-folders 22 and 22^a, the bottom side-folders 23 and 23^a, the top side-folders 24 and 24^a, the fold-retaining members 25 and 25^a, and the adhesive applying discs 26 and 26^a, as elements substantially 45 similar thereto have already been embodied

in apparatus for wrapping blocks or like articles.

50 I would now describe operable means, in accordance with my invention whereby laterally disposed portions of the wrapper 6 70 which project beyond the article 17, at the open-end of the pouch or pocket-like covering (as seen as *w*, *w*, in Figure 5) can be folded on to the adjacently disposed end of the partially wrapped article 17, and also 75 whereby the said article 17 (with its wrapper 6) can be removed or conveyed out of, or away from, engagement with its corresponding travel-imparting pusher 16, to the aforementioned vertically arranged chute.

80 In proximity to each side of the path along which the articles 17 with their corresponding wrappers 6 are actuated to travel, and conveniently near to the aforementioned vertical chute, a set of motion-imparting elements is arranged.

85 Referring more particularly to Figures 1, 2, and 3, a pair of spindles 27 and 27^a are respectively supported in bearings 28 and 28^a.

90 A toothed bevel-wheel 29 and cam 30 are secured to the lower end of the spindle 27, and a disc 31 having a crank-pin 32 is secured to the upper end thereof. A similar arrangement of toothed bevel-wheel 29^a, cam 30^a, disc 31^a, and crank-pin 32^a, is provided 95 in respect of the spindle 27^a.

100 A top spindle 33 is supported at its ends in bosses 34 and 34^a provided respectively on the side-frames 1 and 2, and a bottom-spindle 35 is supported in a similar manner by bosses 36 and 36^a arranged on the said side-frames 1 and 2.

105 The bearing 28 is arranged on a bracket 37 supported by bosses 38 and 39 on the top-spindle 33, and by a boss 40 on the bottom-spindle 35, whilst the bearing 28^a is arranged on a bracket 37^a supported by bosses 38^a and 39^a on the top-spindle 33, and by a boss 40^a on the bottom-spindle 35.

110 A shaft 41 is rotatably supported in bosses 42 and 42^a respectively provided on the side-frames 1 and 2. A pair of toothed bevel-wheels 43 and 43^a are secured to, and are rotatable by means of, the shaft 41.

115 The teeth of the bevel wheel 43 are adapted to engage with the teeth of the bevel-wheel 29, and the teeth of the bevel-wheel 43^a are adapted to engage with the teeth of the bevel-wheel 29^a.

120 Rotative movement is imparted, by an arrangement of toothed gear-wheels, or other suitable means to the shaft 41 and is communicated by the bevel-wheels 29, 43, 29^a and 43^a to the cams 30 and 30^a, and also 125 through the spindles 27 and 27^a to the discs 31 and 31^a.

130 A pair of folding blades, which will be referred to in a more particular manner presently, are provided and are operable to

fold the aforementioned projecting portions α , α , of the wrapper 6 on to the end of the articles 17.

One of the said folding-blades is carried on a bar which is jointably connected by a pin 44 to a lever 45 which is oscillatably supported, by means of a pin 46 on a roller arm 47.

A spindle 48 is supported on the bracket 37, and the roller arm 47 is oscillatably carried thereon. A roller 49 is arranged on the roller arm 47, and the cam 30 imparts suitably timed movements to the roller 49 and thereby to the roller-arm 47.

10 The lever 45 is operably connected, by means of a link 50 and pin 51, to the crank-pin 32.

The bar 52, on which the said folding-blade is carried, is provided with a pin 53.

20 A system of linkwork is provided in connection with the said folding-blade operating means and is adapted to coact with the said operating-means and thereby cause the said folding-blade to move in a certain pre-

25 determined path relatively to the particular article 17 and wrapper 6 on which the said blade is, at the time being, actuated to operate.

The said system of link-work includes a 30 bell-crank 54 pivotally supported on the pin 46. The end of one arm of the bell-crank 54 is jointably connected by a link 55 and pin 56 to a pin 57 arranged on the afore- said bracket 37. The end of the other arm

35 of the bell-crank 54 is provided with an eye-bolt 58, in which the screw-threaded end of a rod 59 is slidably supported. The other end 60 of the rod 59 is jointably attached by means of the pin 53, to the bar 52.

40 A coil-spring 61 is arranged on the rod 59 between the end 60 and the eye-bolt 58. A nut 62 is screwed on to the threaded end of the rod 59.

I have described an arrangement of motion-transmitting members and link-work operable in connection with the folder-blade which is provided on the bar 52 shewn on the lower portion of Figure 2.

45 A similar arrangement of motion-transmitting members and link-work is provided in connection with the folder-blade which is provided on a bar 52^a shewn on the upper portion of Figure 2; the said similar arrangement of members and link-work is 50 shewn on the accompanying drawings, but we have not deemed it necessary to number all of the individual elements which comprise the said similar arrangement.

55 One form of construction of the aforementioned folding-blades and adjacently disposed co-operating members, in accordance with our invention, is shewn in Figures 2, 7, 8, and 9.

60 A pair of retaining bars 63 and 63^a are 65 supported respectively on the aforemen-

tioned bottom-plates 21 and 21^a, and are arranged one on each side of the path along which the articles 17 with their corresponding wrappers 6 are actuated to travel. The said retaining-bars 63 and 63^a are adapted 70 to retain an article 17 with its wrapper 6 in the said path whilst the wrapper 6 of the said article 17 is operated on by folding- blades 64 and 64^a.

75 It will be understood that, in the arrangement I am now describing, the folding-blades 64 and 64^a are carried respectively on the bars 52 and 52^a.

80 The folding-blades 64 and 64^a are respectively provided with gaps or slots 65 and 65^a, or are of bifurcated shape (see Figures 7 and 9) so that the said folding-blades 64 and 64^a can be actuated to fold (in a manner to be more particularly described presently) the projecting portions α , α , of the 85 wrapper 6, on to the end of the article 17, without coming into engagement with the respective adjacently disposed retaining-bars 63 and 63^a.

85 The folding-blade 64 is actuable, by 90 means of the toothed bevel-wheel 29, cam 30, and the arrangement of motion-transmitting members and link-work hereinbefore described in connection therewith, in such manner that the portion W of the 95 said folding-blade 64, is caused thereby to travel along the path and in the direction indicated by the dot-and-dash line and arrow-heads shewn in connection therewith on Figure 15, whilst the folding-blade 64^a 100 is actuable, by means of the toothed bevel-wheel 29^a, cam 30^a, and the arrangement of motion-transmitting members and link-work hereinbefore mentioned in connection therewith, in such similar manner that the portion W^a of the 105 said folding-blade 64^a is caused thereby to travel along the path and in the direction indicated by the dot-and-dash line and arrow-heads shewn in connection therewith on Figure 8, so that the folding-blades 110 64 and 64^a will fold the portions α , α , of the wrapper 6 on to the adjacently disposed end of the article 17, in such manner that the said article 17, with its wrapper 6, will present the appearance shewn in Figure 6. 115

120 The function of the coil-spring 61 on the rod 59 is to impart yieldable pressure on the folding-blade 64, whilst a coil-spring similarly arranged in respect of the folding-blade 64^a imparts yieldable pressure on the said folding-blade 64^a, so that, in the event of any obstruction presenting itself to either or to both of the said folding-blades 64, 64^a, the herein-described apparatus can continue to operate without the liability of damage to, or breakage of, the constituent members thereof.

125 At the same time as, or as soon as, convenient after, the folding of the portions α , α , of the wrapper 6 has been effected by 130

the hereinbefore described operation of the folding-blades 64 and 64^a, and whilst the said folding-blades 64 and 64^a are retained in engagement with and are holding the 5 said portions α , α , of the wrapper 6 on to the adjacently disposed end of the partially wrapped article 17, the respective bars 52 and 52^a on which the said folding blades 64 and 64^a are supported, are operated, by the 10 motion-transmitting members already mentioned in connection therewith, at a conveniently rapid rate of movement, to cause the said folding-blades 64 and 64^a to move, in forward directions (as indicated on Figure 8) and thereby remove or convey the aforesaid partially wrapped article 17, with its wrapper 6, in advance of, and away from engagement with, its corresponding travel-imparting pusher 16, to the aforementioned 15 vertically arranged chute.

It may be stated here that, in accordance with my invention, a lip-shaped projection 66 may be provided on each of the pushers 16, and adapted to engage with, and afford 20 support to, the underside of the respective article 17 which is actuated by its corresponding pusher 16 (see Figure 1).

The aforesaid vertical chute comprises a 25 pair of channel-shaped members 67 and 67^a supported respectively, each in a vertical position, on the aforesaid side-frames 1 and 2.

In proximity to the lower end of the said 30 vertical chute a plate 68 is supported on the upper end of a bar 69.

A lever 70 is oscillatably supported on the 35 top spindle 33 and a roller-arm 71, provided with a roller 72, is oscillatably supported on the bottom spindle 35.

The bar 69 is connected by means of a pin 40 73 to the free-end of the lever 70, and by means of a pin 74 to the free-end of the roller-arm 71. A cam 75, secured to, and rotatable by means of, the shaft 41 imparts 45 suitably timed movements to the roller-arm 71, and the bar 69 with the plate 68 is thereby actuated to move up and down through a convenient distance.

The folding-blades 64 and 64^a are operable (by means of the motion-transmitting 50 members hereinbefore mentioned in connection therewith) to cause the hereinbefore mentioned partially wrapped article 17 with its corresponding wrapper 6 to pass through an opening 76 provided in the lower portion 55 of the aforementioned vertical chute, and to deliver the said article 17 and its partially folded wrapper 6 on to the plate 68 which at this time occupies a lowered position relatively to the said vertical chute.

The folding-blades 64 and 64^a retain the 60 said article 17 with its wrapper 6, for a convenient and relatively short period, on the plate 58, whilst a folding-blade 77 is operated to fold that projecting portion of the 65 wrapper 6 which is adjacent to the under-

surface of the partially wrapped article 17, up and on to the end of the article 17, (see Figure 12).

The said folding-blade 77 is provided on, or is secured to, the free-end of a lever 78 70 extending from a boss 79 which is oscillatably supported on the spindle 33. A roller-arm 80 extends from the boss 79 and is provided with a roller 81. A cam 82, secured to, and rotatable by means of, the shaft 41 75 imparts suitably timed movements to the roller-arm 80, and thereby to the lever 78 and folding-blade 77.

In proximity to the lower end of the aforesaid vertical chute a pair of sets of 80 package-retaining elements are provided.

The plate 68 is actuated by the motion-imparting members, already mentioned in connection therewith, to move in an upward direction and thereby push the aforesaid 85 partially wrapped article 17 with its wrapper 6, past and above the package retaining elements.

The said upward movement of the said 90 partially wrapped article 17 and wrapper 6, causes the lower edges 94 and 94^a of the respective channel-shaped members 67 and 67^a (see Figures 12 and 13) to coact with the wrapper 6 to fold a portion of the wrapper 95 6 which is adjacent to the upper surface of the partially wrapped article 17 in the vertical chute, on to these portions of the wrapper 6 which have been folded already (by the means and in the manner herein set forth) on to the end of the article 17, 100 so that the said article 17 with its wrapper 6 will be caused thereby to appear as shewn in Figure 4.

A modified construction of the said folding-blades and adjacently disposed members, also in accordance with my invention, 105 is shewn in Figures 10 and 11. These folding blades and associated parts are adapted to replace the blades 64 and 64^a.

A pair of retaining elements are arranged in respect of each side of the hereinbefore mentioned path of travel of the 110 articles 17.

One pair of the said retaining elements and a corresponding folding-blade are operably provided in proximity to the channel-shaped member 67 of the vertical chute and are shewn in the said Figures 10 and 11; a similar pair of retaining elements and a corresponding and similar folding-blade are operably provided in proximity to the channel-shaped member 67^a, but are 115 not shewn on the accompanying drawings.

Extension arms 95 and 96 are provided 120 on the channel-shaped member 67.

Retaining elements 97 and 98 are respectively supported, in a pivotal manner by pins 99 and 100 on the extension arms 95 and 96 and are parallel to the path of movement of the article to be wrapped. A spring 125 130

101 is arranged on the pin 99, and yieldably actuates the retaining element 97 to move towards the adjacent side of the aforementioned article 17; a similar spring 102 is provided in respect to, and actuates the retaining element 98 in a similar manner.

The retaining elements 97 and 98 and the aforementioned corresponding pair of retaining elements which are provided in respect of the channel-shaped member 67^a are adapted to retain the aforesaid article 17 with its corresponding wrapper 6 in the aforementioned rectilinear path of travel whilst the said article 17 and its wrapper 6 are operated on by the folding-blade 103 and the similar folding-blade which operates in proximity to the channel-shaped member 67^a to fold or tuck in the parts XX shown in Figure 14.

20 Gaps 105 are provided in conveniently arranged positions in the retaining elements 97 and 98 in order to allow the folding-blade 103 to come into, and withdraw from, operative engagement with the aforesaid article 17 and corresponding wrapper 6.

It will be understood that the shank-piece 104 of the folding blade 103 can freely pass to and fro in the space between the edges of the respective retaining elements 97 and 98, and the spring actuated and yieldable manner in which the said retaining elements 97 and 98 are supported on their respective pins allows the folding-blade 103 to be withdrawn from engagement with the said wrapper 6 35 and article 17 even if, for any reason, the folding-blade 103 is not, at the particular time, opposite or in normal withdrawing position relatively to either of the said gaps 105.

40 The folding blade 103 carried by the shank 104 and the corresponding blade on the other side of the path of the article to be wrapped are adapted to be inserted thru the passages 105 the furthest to the left in Figure 10 and simultaneously with its insertion to fold in the parts of the pouch extending behind the article as shown at XX in Figure 6. The blade not only moves inwardly but longitudinally of the article and after the folding 45 operation continues to move the article in its direction of motion along the path but at a greater speed than that imparted to the same by the follower. The folding blade 103 continues to move the wrapped article and serves to push it thru the opening 76 in the vertical chute and on to the plunger 68 in a manner identical with that of the folding blade 64. Motion may be imparted to the blade 103 by any suitable mechanism, 55 preferably one substantially identical with that described in connection with the folding blade 64.

60 It will be obvious that in the herein-described apparatus a pair of sets of elements are provided and arranged one set on one

side of, and the other and similar set on the other side of, the path along which the said articles 17 with their wrappers 6 are actuated to travel.

A feature of my present invention consists in that one of the said sets of elements (which I will term the adjustable set) is arranged at a convenient distance from the other said set of elements (which other set I will term the non-adjustable set) and the several parts which constitute the said adjustable set can be readily and quickly altered and adjusted by any suitable means, such as for example, the slotted brackets 106, 107, 109, 110, and 111, the aforesaid bosses 38 and 39, bolts 112, 113, 114, 115, 116, and 117, and screws 118, and 119, shewn on Figure 2, relatively to the corresponding parts which constitute the aforesaid non-adjustable set of elements, so that by suitable adjustment of the parts of the said adjustable set of elements, and without disturbing or interfering with the corresponding parts of the said non-adjustable set of elements, an attendant can render the herein-described apparatus suitable at one time for wrapping articles of a certain width, and at another time for wrapping articles of a relatively lesser or greater width.

Having now particularly described and ascertained the nature of my said invention and in what manner the same is to be performed, I declare that what I claim is:

1. In a wrapping machine of the class specified for wrapping articles in paper or like material, the combination of a continuously moving conveyor for advancing the articles in succession along a fixed path, folding devices operable during the advance of each article to fold a wrapper about it to the form of an open-ended pouch whereof the open end is adjacent to and projects beyond the rear end-face of the article, and means operable near the end of the conveyor path to engage the aforesaid rear end-face of each pouch-enclosed article and to move said article ahead of the conveyor at a speed greater than that of the conveyor and to a position clear of the latter.

2. In a wrapping machine of the class specified for wrapping articles in paper or like material, the combination of a continuously moving conveyor for advancing the articles in succession along a fixed path, folding devices operable during the advance of each article to fold a wrapper about it to the form of an open-ended pouch whereof the open end is adjacent to and projects beyond the rear end-face of the article, and means located near the end of the conveyor path and operable on each pouch-enclosed article first to engage and tuck in the sides of the aforesaid projecting portion of the pouch and thereafter by end-on engagement with the article to advance the latter to a

position clear of the end of the conveyor and at a speed greater than that of said conveyor.

3. In a wrapping machine of the class specified for wrapping articles in paper or like material, the combination of a continuously moving conveyor for advancing the articles in succession along a fixed path, folding devices operable during the advance of each article to fold a wrapper about it to the form of an open-ended pouch whereof the open end is adjacent to and projects beyond the rear end-face of the article, transfer members mounted near the end of the conveyor path for movement in a plane containing said path and on opposite sides thereof respectively, and means operable on the approach of each pouch-enclosed article to bring the transfer members aforesaid into engagement with the rear end-face of the article, then to move said members ahead of the conveyor to a position beyond the end thereof and at a speed greater than that of the conveyor, and thereafter to withdraw the transfer members from engagement with the article and to return them to their initial positions.

4. In a wrapping machine of the class specified for wrapping articles in paper or like material, the combination of a continuously moving conveyor for advancing the articles in succession along a fixed path, folding devices operable during the advance of each article to fold a wrapper about it to the form of an open-ended pouch whereof the open end is adjacent to and projects beyond the rear end-face of the article, transfer members mounted near the end of the conveyor for movement in the plane of the advancing articles and on opposite sides thereof respectively and means operable on the approach of each pouch-enclosed article first to move the transfer members against the sides of the projecting end-portion of the pouch and into the path of the conveyor, then to move the transfer members along said path at a speed greater than that of the conveyor and to a position beyond the end of the latter, and thereafter to withdraw the transfer members from the path of the article and to return them to their initial positions.

5. In a wrapping machine of the class specified for wrapping articles in paper or like material, the combination of a continuously moving conveyor for advancing the articles in succession along a fixed path, folding devices operable during the advance of each article to fold a wrapper about it to the form of an open-end pouch whereof the open end is adjacent to and projects beyond the rear end-face of the article, transfer members mounted near the end of the conveyor for movement in the plane of the advancing articles and on opposite sides there-

of respectively, means operable on the approach of each pouch-enclosed article first to move the transfer members against the sides of the projecting end-portion of the pouch and into the path of the conveyor, then to move the transfer members along said path at a speed greater than that of the conveyor and to a position beyond the end of the latter, and thereafter to withdraw the transfer members from the path of the article and to return them to their initial position, the aforesaid means for moving the transfer members being constituted by a separate mechanism allocated to each member and comprising a link mounted at one end on a floating pivot and at the other end operatively connected to the transfer member, means for oscillating the link about its pivot in a direction to move the transfer member substantially parallel with the conveyor path, and means to reciprocate the floating pivot aforesaid in a direction transverse to the conveyor path.

6. In a wrapping machine of the class specified for wrapping articles in paper or like material, the combination of a continuously moving conveyor for advancing the articles in succession along a fixed path, folding devices operable during the advance of each article to fold a wrapper about it to the form of an open-ended pouch whereof the open end is adjacent to and projects beyond the rear end-face of the article, transfer members mounted near the end of the conveyor for movement in the plane of the advancing articles and on opposite sides thereof respectively, means operable on the approach of each pouch-enclosed article first to move the transfer members against the sides of the projecting end-portion of the pouch and into the path of the conveyor, then to move the transfer members along said path at a speed greater than that of the conveyor and to a position beyond the end of the latter, and thereafter to withdraw the transfer members from the path of the article and to return them to their initial positions, and means to constrain each transfer member to move parallel to itself throughout its whole travel.

7. In a wrapping machine of the class specified for wrapping articles in paper or like material, the combination of a continuously moving conveyor for advancing the articles in succession along a fixed path, folding devices operable during the advance of each article to fold a wrapper about it to the form of an open-ended pouch whereof the open end is adjacent to and projects beyond the rear end-face of the article, transfer members mounted near the end of the conveyor for movement in the plane of the advancing articles and on opposite sides thereof respectively, means operable on the approach of each pouch-enclosed article first

- to move the transfer members against the sides of the projecting end-portion of the pouch and into the path of the conveyor, then to move the transfer members along said path at a speed greater than that of the conveyor and to a position beyond the end of the latter, and thereafter to withdraw the transfer members from the path of the article and to return them to their initial positions, the aforesaid means for moving the transfer members being constituted by a separate mechanism allocated to each member and comprising a link mounted at one end on a floating pivot and at the other end 10 operatively connected to the transfer member, means for oscillating the link about its pivot in a direction to move the transfer member substantially parallel with the conveyor path, means to reciprocate the floating pivot aforesaid in a direction transverse to the conveyor path, and means to constrain each transfer member to move parallel to itself throughout its whole travel.
8. In a wrapping machine of the class specified for wrapping articles in paper or like material, the combination of a continuously moving conveyor for advancing the articles in succession along a fixed path, folding devices operable during the advance 15 of each article to fold a wrapper about it to the form of an open-ended pouch whereof the open end is adjacent to and projects beyond the rear end-face of the article, two transfer members mounted near the end of the conveyor for movement in the plane of the advancing articles and on opposite sides thereof respectively, a reciprocating mechanism for each transfer member comprising means operable on the approach of each pouch-enclosed article first to close the transfer member against the side of the projecting portion of the pouch and into engagement with the rear end-face of the article, then to move the transfer member forward at a speed greater than that of the conveyor and to a position beyond the end of the latter and thereafter to withdraw the member from engagement and to return it to its initial position, and a lost-motion connection and a spring between each transfer member and its reciprocating mechanism, normally operative to take up the lost motion in said connection.
9. In a wrapping machine of the class specified for wrapping articles in paper or like material, the combination of a continuously moving conveyor for advancing the articles in succession along a fixed path, folding devices operable during the advance 20 of each article to fold a wrapper about it to the form of an open-ended pouch whereof the open end is adjacent to and projects beyond the rear end-face of the article, stationary guides positioned near the end of the conveyor on opposite sides thereof and arranged to engage the sides of the advancing articles, transfer members mounted side-by-side with the guides aforesaid and movable into and out of the space enclosed between them, and means operable when a pouch-enclosed article is located between the guides aforesaid to move the transfer members against the sides of the projecting end-portion of the pouch and into engagement with the end-face of the article, then to advance the transfer members to a position beyond the end of the conveyor and at a speed greater than that of said conveyor, and thereafter to withdraw said members from engagement and to return them to their initial positions.
10. In a wrapping machine of the class specified for wrapping articles in paper or like material, the combination of a continuously moving conveyor for advancing the articles in succession along a fixed path, folding devices operable during the advance 25 of each article to fold a wrapper about it to the form of an open-ended pouch whereof the open end is adjacent to and projects beyond the rear end-face of the article, stationary guides positioned near the end of the conveyor on opposite sides thereof respectively and arranged to engage substantially centrally along the sides of the advancing articles, transfer members mounted side-by-side with the guides aforesaid and recessed to accommodate the guides and permit movement of the transfer members into and along the space enclosed between said guides, and means operable when a pouch-enclosed article is located between the guides aforesaid to move the transfer members against the sides of the projecting end-portion of the pouch and into engagement with the end-face of the article, then to advance the transfer members to a position beyond the end of the conveyor and at a speed greater than that of said conveyor, and thereafter to withdraw said members from engagement and to return them to their initial positions.
11. In a wrapping machine of the class specified for wrapping articles in paper or like material the combination of a continuously moving conveyor for advancing the articles in succession along a fixed path, two sets of folding devices located on opposite sides respectively of said path and operable during the advance of each article to fold a wrapper about it to the form of an open-ended pouch whereof the open-end is adjacent to and projects beyond the rear end-face of the article, two transfer members located near the end of the conveyor and on opposite sides respectively of the aforesaid fixed path, two reciprocating mechanisms associated respectively with the two transfer members and operable to bring said members into engagement with the rear

end-face of each pouch-enclosed article and thereafter to advance said members to a position beyond the end of the conveyor and at a speed greater than that of the latter, and means to permit of the folding devices, transfer member and its associated reciprocating mechanism, which operate on one side of the machine being adjusted to vary the spacing between them and their 10 companion elements which operate on the other side of the machine.

12. In a wrapping machine of the class specified for wrapping articles in paper or like material, the combination of an endless 15 chain conveyor whereof the upper lap is movable continuously in the same direction along a horizontal path, upstanding pusher pieces spaced apart on the conveyor and adapted to engage the rear ends of the articles 20 and to push the latter at spaced intervals along the aforesaid path, stationary folding devices located above and below and at the sides of the aforementioned path and operable during the advance of each article 25 to fold a wrapper about it to the form of an open-ended pouch whereof the open end is adjacent to and projects beyond the rear end-face of the article, two transfer members mounted near the forward end of the 30 conveyor for reciprocation in the plane of the advancing articles and on opposite sides thereof respectively, and associated with each transfer member a reciprocating mechanism operable on the approach of each 35 pouch-enclosed article to move the transfer member in a direction aslant the conveyor path against the side of the projecting end-portion of the pouch and thence into engagement with the rear end of the article, 40 then to move the transfer member forward to a position clear of the end of the conveyor and at a speed greater than that of said conveyor, and thereafter to withdraw the transfer member from engagement with 45 the article and to return said member to its initial position.

13. In a wrapping machine of the class specified for wrapping articles in paper or like sheet material the combination of conveyor means for advancing the articles in 50 succession along a fixed path, folding devices operable during the advance of each

article to fold a wrapper about it to the form of an open-ended pouch whereof the open end is adjacent to and projects beyond 55 the rear end-face of the article, tucking elements mounted on opposite sides respectively of the aforesaid fixed path for reciprocatory movement into said path, and means operable when a pouch-enclosed article is 60 adjacent to the tucking elements first to close said elements against the sides of the aforesaid projecting portion of the pouch and into engagement with the rear end-face 65 of the article, then to move the tucking elements forward along the path aforesaid and thereafter to withdraw said elements from engagement with the article and to return them to their initial positions by a backward movement parallel with the path 70 aforesaid.

14. In a wrapping machine of the class specified for wrapping articles in paper or like sheet material the combination of conveyor means to advance the articles in succession along a fixed path, folding devices operable during the travel of each article along the path aforesaid to fold a wrapper about it in the form of an open-ended pouch whereof the open end is adjacent to and projects beyond the rear end-face of the article, stationary guides located on opposite sides of the path aforesaid and arranged to engage the sides of the pouch-enclosed articles, tucking elements located side by side 80 with the guides aforesaid and movable into and out of the space enclosed between them, means operable when a pouch-enclosed article is located between the guides aforesaid to close the tucking elements against the 85 sides of the projecting end portion of the pouch and into engagement with the rear end-face of the article, then to move the tucking elements forward along a continuation of the aforesaid fixed path and thereafter to withdraw said elements from engagement with the article and to return them to their initial positions, and means 90 to constrain each tucking element to move parallel to itself throughout its whole travel. 95 100

In testimony whereof I affix my signature.

WILLIAM ROSE.
